United States Patent Office

Des. 208,307
Patented Aug. 15, 1967

208,307

ENTRANCE HEAD OR SIMILAR ARTICLE FOR WIRES AND THE LIKE

Wesley A. Weber and Terry J. Hurtt, Aurora, Ill., assignors to All-Steel Equipment Inc., Aurora, Ill., a corporation of Illinois

Filed Feb. 23, 1966, Ser. No. 1,158

Term of patent 14 years

(Cl. D26—5)

FIGURE 1 is a perspective view of the entrance head, showing our design;

FIGURE 2 is a perspective view of our entrance head, showing in more detail the back thereof;

FIGURE 3 is a front view of the entrance head with the cover thereof lifted away to better illustrate same;

FIGURE 4 is a side plan view of the entrance head; and

FIGURE 5 is a back view of the entrance head.

We claim:

The ornamental design for an entrance head or similar article for wires and the like, substantially as shown.
